US00D591695S

(12) **United States Design Patent**
Oh et al.

(10) **Patent No.:** US D591,695 S
(45) **Date of Patent:** ** May 5, 2009

(54) **LIGHT-EMITTING DIODE MODULE**

(75) Inventors: **Kyung Seob Oh**, Incheon (KR); **Min Sang Lee**, Gyunggi-do (KR); **Tae Hong Lee**, Seoul (KR)

(73) Assignee: **Samsung Electro-Mechanics Co., Ltd.**, Gyunggi-Do (KR)

(**) Term: **14 Years**

(21) Appl. No.: **29/290,410**

(22) Filed: **Dec. 4, 2007**

(30) **Foreign Application Priority Data**

Jul. 11, 2007 (KR) 30-2007-0030131

(51) **LOC (9) Cl.** 13-03

(52) **U.S. Cl.** D13/180

(58) **Field of Classification Search** D13/180; D26/1, 24, 72, 89; 257/79, 80, 81, 88, 89, 257/95, 98, 99, 100, 678; 313/483, 498, 313/500; 362/555, 800; D7/554.2; D21/307, D21/308; 118/500

See application file for complete search history.

(57) **CLAIM**

The ornamental design for the light emitting diode module, as shown and described.

DESCRIPTION

FIG. 1 is the perspective view of the light emitting diode module

FIG. 2 is the front view thereof (the rear view thereof is a mirror image of this)

FIG. 3 is the left view thereof (the right side view thereof is a mirror image of this)

FIG. 4 is the top plan view thereof

FIG. 5 is the bottom view thereof; and,

FIG. 6 is a bottom perspective view thereof.

The broken line showing of the environment is for illustrative purposes only and forms no part of the claimed design.

1 Claim, 4 Drawing Sheets

FIG. 1

FIG. 2

FIG. 3

FIG. 4

FIG. 5

FIG. 6
